JEWELRY

Adolph Katz, New York, N. Y., assignor to Cohn & Rosenberger, Inc., New York, N. Y., a corporation of New York

Application July 21, 1933. Serial No. 681,473

6 Claims. (Cl. 63—20)

This invention relates to jewelry and particularly to convertible articles of variable appearance and utility.

It is the object of the invention to provide an article of jewelry having a dismountable portion adapted to be used separately and a construction therefor which facilitates the assembling and dismounting of the parts.

The invention is applicable to various forms 10 of jewelry, but will be illustrated for convenience as applied to a brooch embodying a dismountable clip. The invention as thus embodied will be better understood by reference to the following specification and accompanying drawing, in 15 which

Fig. 1 is a front elevation of the brooch with the parts assembled;

Fig. 2 is a rear elevation of the structure as shown in Fig. 1;

20 Fig. 3 is a rear elevation of the brooch with the clip and supporting bridge removed;

Fig. 4 is a rear elevation of the brooch with the bridge in position;

Fig. 5 is a view in perspective of the clip;

25 Fig. 6 is a plan view of the bridge; and Fig. 7 is a section on the line 7—7 of Fig. 1.

Referring to the drawing, 5 indicates the brooch which may be of any ornamental design embodied in any suitable metal and ornamented, 30 if desired, with stone, imitations thereof, or other decorative features. The brooch is provided with a pin 6 pivotally secured at 7 and adapted to be held in closed position by a clasp 8 whereby the brooch may be attached to the 35 clothing, for example. As indicated particularly in Fig. 3, the brooch may be utilized as such, independently of the clip 9, which is associated therewith in Fig. 1. When the two parts are thus assembled, a brooch of different appearance 40 is provided. When the clip has been removed, it may be used independently.

The clip, as indicated in Fig. 5, comprises a member 10 having a decorative facing as illustrated in Fig. 1, and the clip is provided with 45 lugs 11 to pivotally receive the end of a leg 12. A spring 13 is secured at 14 to the member 10 and at 15 to the leg 12 and is arranged so that it holds the leg 12 either in open or closed position as the leg swings past the center in either direction. The leg 12 may be provided with 50 points 16 which are adapted to engage the garment, whereby the clip is held securely in any desired position.

To assemble the clip with the brooch 5, a bridge 55 17 is removably supported on the brooch in any

suitable manner. A satisfactory arrangement is the provision of pins 18 on the brooch having slightly enlarged heads and adapted to receive the split ends 19 of the bridge. When these ends engage the pins 18, the resilience of the split ends holds the bridge securely in position. Any other suitable arrangement to accomplish the purpose may be employed. The bridge is provided preferably with a notch 20 to accommodate the spring 13 on the clip 9 when the clip is assembled with 60 the brooch.

To assemble the parts the leg 12 is inserted through the opening between the bridge and the brooch from the face thereof, and is moved to closed position as indicated in Figs. 2 to 7. An 70 extension 21 on the member 10 of the clip engages a similar extension 22 on the bridge as indicated in Fig. 2, thus affording a support and assuring maintenance of the parts in their proper assembled relation. When thus assembled, the parts 75 have the appearance indicated in Fig. 1 of the drawing.

From the foregoing description, it will readily be understood that the device affords a simple and effective construction permitting the assembling and dismounting of the parts and the independent use thereof. The device may be utilized, therefore, as two articles of jewelry or may be combined in a single piece to provide a brooch 80 of different appearance.

85 Various changes may be made in the structure and arrangement of the parts, and the invention may be applied to other articles of jewelry, without departing from the invention or sacrificing any of the advantages thereof.

90 I claim:

1. An article of jewelry comprising a member having a decorative facing, a removable bridge supported on the member and a separable member having a decorative facing adapted to engage 95 the bridge and to be supported thereby.

2. An article of jewelry comprising a member of annular form having a decorative facing, a removable bridge supported on the annular member and a separable member having a decorative 100 facing and a pivoted leg adapted to embrace the bridge and to be supported thereby.

3. An article of jewelry comprising a brooch having a decorative facing, a removable bridge supported on the brooch and a clip having a decorative facing and a pivoted leg adapted to embrace the bridge and to be supported thereby.

4. An article of jewelry comprising a member having a decorative facing, spaced pins projecting from the member, a removable bridge sup- 110

ported on the pins and a separable member having a decorative facing adapted to engage the bridge and to be supported thereby.

5. An article of jewelry comprising a member having a decorative facing, spaced pins projecting from the member, a removable bridge having split ends to engage and to be supported on the pins and a separable member having a decorative facing adapted to engage the bridge and to be supported thereby.

6. An article of jewelry comprising a brooch having a decorative facing, spaced pins projecting from the brooch at the rear thereof, a removable bridge engaging and supported on the pins and a clip having a decorative facing and a leg adapted to embrace the bridge and to be supported thereby.

ADOLPH KATZ.
